(57) CLAIM

We claim the ornamental design for a remote control, as shown and described.

DESCRIPTION

FIG. 1 shows a first perspective view of the remote control;
FIG. 2 shows a front view of the remote control;
FIG. 3 shows a rear view of the remote control;
FIG. 4 shows a first side view of the remote control;
FIG. 5 shows a second side view of the remote control;
FIG. 6 shows a top side view of the remote control; and,
FIG. 7 shows a bottom side view of the remote control.
The portions shown in broken lines form no part of the claimed design.
